UNITED STATES PATENT OFFICE.

JOSEPH MATALONI, OF MASON CITY, IOWA.

KEY HOLDER.

Application filed May 5, 1925. Serial No. 28,108.

To all whom it may concern:

Be it known that I, JOSEPH MATALONI, a subject of the King of Italy, residing at Mason City, in the county of Cerro Gordo 5 and State of Iowa, have invented certain new and useful Improvements in Key Holders, of which the following is a specification.

This invention relates to improvements 10 in keyholders and it is the principal object of the invention to provide a key-holder, the ring or loop of which is locked in a novel and convenient manner to allow the ready attachment and removal of keys.

Another object of the invention is the 15 provision of a key-holder of a simple and inexpensive construction adapted to be readily attached to a support.

A further object of the invention is the 20 provision of a key holder allowing a convenient swinging about its pivot when unlocked.

A still further object of the invention is the 25 provision of a key-holder equipped with a double locking and releasing means for the key-holder.

These and other objects and advantages 30 of the invention will become more fully known as the description thereof proceeds, and will then be specifically defined in the appended claim.

In the accompanying drawing, forming a material part of this disclosure:

Fig. 1 is a front elevation of a key- 35 holder constructed according to the present invention.

Fig. 2 is an end view thereof.

Fig. 3 is a sectional front elevation of the 40 key-holder and the locking means.

Fig. 4 is a section on line 4—4 of Figure 3.

Fig. 5 is a sectional elevation of a modified form of locking means.

Fig. 6 is a section on line 6—6 of Figure 5.

Fig. 7 is a sectional elevation of another modified form of locking means.

The key holder comprises a block 10 to which a hanger 11 is secured in any well known manner.

The block 10 has a lateral bore 12 near one 50 of its side edges for the reception of the upper end of one shank of a strong wire loop 13 which has a circumferential groove 14 adapted to be engaged by a pin 15 in block 10 allowing a rotation of the loop

shank while holding it securely attached to the block.

The loop 13 has a suitable curvature and its opposite end is provided with a notch 16 or the like, adapted to be introduced 60 into a bore 17 of the block 10 near the opposite end wall of the same, having bore 12 therein and parallel thereto. A horizontally disposed bore 18 has slidably guided therein a pin 19, shorter than the bore, 65 and a spring 20 is located within said bore resting against the inner end of said pin 19 and the inner end wall of the bore 18. The pin is held and guided during its movements by a pin 21 projecting through a transverse 70 channel 22 to the outside of the block adapted to be gripped by the fingers. The outer end of the pin 19 is beveled or reduced as at 23, and adapted to engage into the notch 16. 75

The holder is hung in the usual manner from a hook 24 suitably bent to be hung from any suitable support 25.

The modification of the device illustrated in Figures 5 and 6 shows the hanger 11 attached to a block 26 having a bore 27 therein for the reception of one shank end of loop 13 which has a cut-away portion 28 in its side wall and also a circumferential groove 14 near its upper end, while the pin 15 85 traveling along the cut-away portion 28 allows a displacement of the shank of 13 within certain limits and by engagement with groove 14 prevents an entire withdrawal, while allowing a rotation of the shank 13. 90 The other shank of loop 13 is adapted to be introduced into a bore 17 of block 26 and has a circumferential groove 29 adapted to be engaged by a pin 30 entering a lateral bore of block 26. On its opposite side said 95 groove 29 is engaged by the end of the pin 19 moving in the bore 18 in which the spring 20 bears against the end of said pin and against the end wall of the bore, while a pin 31 moving in a recess 32 of block 26 100 limits the movements of pin 19.

The modification illustrated in Figure 7 combines the forms shown in Figures 4 and 5, having an upper gripping pin 33 and a lateral operating pin 34 for the operation 105 of the pin 19.

The operation of the device will be entirely clear from the above description, the operation of the pins by means of handles 21, 30, 33 and 34, will release the shank of 110

loop 13, and allow a rotation of the same about its pivot 14 and 15, so that keys, etc. may conveniently be attached or removed thereto, whereafter the shank is locked again in an evident manner.

While the description and drawing illustrate some of the forms of my invention, by way of example, it is to be understood that such changes may be made in the construction of the minor details as fall within the scope of my device without departure from the spirit and principle thereof.

Having thus described my invention, what I claim as new, and desire to secure by Letters Patent, is:

A key-holder comprising a block having two parallel transversal bores therein and a

horizontally disposed bore, a wire loop having a circumferential groove in one of its shanks, and a notch in the other, a pin in said block engaging said groove for holding said loop in said block against withdrawal but permitting a rotation of the same, a spring controlled pin in said horizontal bore adapted to engage the notch in said loop shank for locking the parts in their engaged positions and a means for breaking said engagement to allow an opening and rotation of said loop for the attachment and removal of keys.

In testimony whereof I have affixed my signature.

JOSEPH MATALONI.
